RAILROAD SIGNAL

Filed June 15, 1927

FIG. 1.

UNITED STATES PATENT OFFICE.

FRANK A. MILLER, OF OAKLAND, CALIFORNIA, ASSIGNOR OF ONE-THIRD TO SELF, ONE-THIRD TO HARRY A. MITCHELL, OF OAKLAND, CALIFORNIA, AND ONE-THIRD TO WALTER ARNSTEIN, OF SAN FRANCISCO, CALIFORNIA.

RAILROAD SIGNAL.

Application filed June 15, 1927. Serial No. 198,924.

My invention relates to signals for use on railways and particularly refers to signals adapted to indicate to the engineer of a train whether or not intersection and crossing signals are operating.

It is now the custom to install automatic warning signals at the intersection of railroad tracks and vehicular highways to warn vehicle operators of the approach of a train on the railroad track. These warning signals are generally bells or wig-wags which afford a visual indication and in some instances an audible indication as well. Ordinarily, the crossing signals are operated during the presence of a train on the track adjacent the signal. This operation is accomplished in a number of different ways and usually includes the closing by a train on the track of an electric circuit either between the two rails of the track or, between the trolley wire of an electric line and the rails. Occasionally such warning signals become inoperative and no warning of the approach of a train is afforded at the intersection. The external appearance of the signal does not indicate that it is out of order and persons such as vehicle drivers approaching the intersection and depending upon the signal are misled. The engineer of the approaching train has no way of telling whether or not the signal is operating and normally assumes that the signal is operative and that vehicle drivers have warning of the approach of the train and proceeds on the basis that the crossing is clear. There is therefore serious possibility of accidents when the warning signal at an intersection becomes inoperative.

It is therefore an object of my invention to provide means for indicating to the engineer of an approaching train whether or not the warning signal at an intersection is operating.

Another object of my invention is to provide a plurality of such indicating signals operated so that the possibility of accidents is further lessened.

A further object of my invention is to provide an indicating means which is readily attachable to the crossing signals at present installed.

An additional object of my invention is to provide rugged and dependable actuating means for the indicator.

My invention possesses other advantageous features some of which with the foregoing will be set forth at length in the following description where I shall outline in full that form of the railroad signal of my invention, which I have selected for illustration in the drawings accompanying and forming part of the present specification. In said drawings I have shown one form of railroad signal embodying my invention, but it is to be understood that I do not limit myself to such form since the invention as set forth in the claims may be embodied in a plurality of forms.

In the drawings:

Fig. 1 is a diagram of a railroad and highway intersection disclosing the installation of my railroad signal thereon.

Fig. 2 shows in transverse section a wig-wag warning of a standard type with the electric contacts for the indicator installed therein.

The railroad signal of my invention preferably comprises an indicating signal actuated upon the approach of a train for indicating to the train engineer whether or not the crossing signal at the intersection is in operation.

In the preferred form of my invention as disclosed in the accompanying drawings I have shown a track 6 comprising a pair of rails which extend across a highway 7. The railroad as illustrated is electric and is provided with a trolley wire 8 for supplying electricity to a train passing along the track. At the intersection of the track 6 and highway 7 warning signals 9 are provided. These warning signals can be of any of the standard kinds but preferably are operated by electricity upon the approach thereto of a train. Each warning signal is preferably a wig-wag, as shown in Fig. 2, comprising a housing 11 mounted on a suitable support 12 at one side of the highway and of the track 6. The housing encloses an electric motor 13 connected thru a pitman 14 to an oscillating banner 16. The electric motor is provided with two conductors 17 and 18, the first of which

is connected to the trolley wire 8 and the second of which is connected to the rails. Upon the approach to the signal 9 of a train upon track 6, the motor 13 is energized and operates to move the banner 16. The banner thereby gives warning to persons such as vehicle operators on the highway 7 that a train is approaching.

In order to indicate to the engineer of the train whether or not the banners 16 are being oscillated, I provide indicators 19 and 21. An indicator 19 is disposed approximately one hundred feet from the signal 9 and an indicator 21 is disposed approximately one thousand feet from the indicator 9. For a track on which trains approach from either direction, I preferably arrange a plurality of indicators 19 and 21 symmetrically on both sides of the intersection.

The indicators preferably are similar and comprise posts on which suitable electric indicating lights are mounted. To render lights operative during the time the warning signals 9 are operating, I preferably provide them with an electric circuit including a source of electricity 22 connected by conductors 23 and 24 to all of the indicators 19 and 21 in series. The indicators can also be connected in parallel and in some installations the parallel connection is preferred.

Controlling the circuit are a pair of contacts 26 and 27 actuated by one of the warning signals 9 and located within the casing 11 thereof. Normally, the contacts 26 and 27 are positioned to open the circuit of the indicators while upon the energization of motor 13, the oscillating banner 16 closes the indicator circuit. This is effected by a hammer 28 on one side of the banner lever 29 which forces contact 26 to touch contact 27 thereby insuring electrical communication. I have found in operation that two spiral springs 26 and 27 are practically trouble proof and afford an electrical contact readily and without severe arcing. They have comparatively a long life and need practically no attention.

If all of the units in the railroad signal are in operating condition, the approach of a train upon track 6 first energizes motors 13 to operate the warning signals 16 while the indicators 19 and 21 are then intermittently energized by the successive closing of contacts 26 and 27 by the associated oscillating banner 16. The engineer of the approaching train when he is approximately one thousand feet from the intersection is informed by the blinking light 21 that the speed of his train need not be slackened as suitable warning is positively being given to users of the highway 7. He continues toward the intersection and further notes when he is approximately one hundred feet therefrom by looking at indicator 19 that the signal is still in

operating condition. If, however, when he approaches indicator 21, he finds that it is not blinking, he immediately reduces the speed of his train and if he finds further that indicator 19 in its turn is not operating, he brings his train to a halt to permit investigation of conditions at the intersection or proceeds at a slow rate of speed.

The engineer is thus given ample warning whether or not the warning signal 9 is functioning and can regulate his train accordingly. The possibility of accidents is considerably lessened and the possibility of inoperative warning signals being neglected is made remote. While I have described my railroad signal as it is applied at a highway intersection, it is equally useful in other environments as will readily appear.

I claim:

1. A railroad signal comprising a warning signal actuated upon the approach of a train, and means intermittently actuated upon the operation of said warning signal for indicating to the engineer of said train the fact of said operation.

2. A railroad signal comprising a warning signal actuated upon the approach of a train, and an intermittently operated indicator spaced from said signal in the direction of approach of said train for indicating the operation of said signal.

3. A railroad signal comprising a warning signal actuated upon the approach of a train, and a plurality of intermittently operated indicators spaced from said signal in the direction of approach of a train and simultaneously indicating the operation of said warning signal.

4. A railroad signal comprising a warning signal actuated upon the approach of a train, a plurality of indicators, and means for intermittently actuating said indicators during the operation of said warning signal.

5. A railroad signal comprising a warning signal actuated upon the approach of a train, an electric indicator spaced from said warning signal in the direction of approach of a train, an electric circuit for said indicator, and means controlled by the operation of said warning signal for intermittently energizing said circuit.

6. A railroad signal comprising a warning signal actuated upon the approach of a train, a plurality of electric lights spaced from each other and from said warning signal in the direction of approach of a train, a series electric circuit for said lights, and means actuated by the operation of said warning signal for intermittently energizing said circuit.

7. A railroad signal comprising a warning signal including an electrically driven moving element an electric circuit for said warning signal, means including a train adjacent said warning signal for energizing

said circuit, an electric indicator adjacent said warning signal, an electric circuit for said indicator, and means actuated by said moving element for periodically energizing 5 said indicator circuit.

8. A railroad signal comprising an element moved during the proximity of trains to said

signal, an electric indicator for said element, and a pair of spiral springs actuated by said element for closing the circuit of said indicator. 10

In testimony whereof, I have hereunto set my hand.

FRANK A. MILLER.
